UNITED STATES PATENT OFFICE

149,066

DESIGN FOR A HYGIENIC SOAP DISH

Barnet D. Kaplan, New York, N. Y., assignor of
one-half to Abner Weiner, Brooklyn, N. Y.

Application December 3, 1946, Serial No. 135,233

Term of patent 14 years

(Cl. D4—3)

To all whom it may concern:

Be it known that I, Barnet D. Kaplan, a citizen of the United States, residing at New York city, in the county of Bronx and State of New York, have invented a new, original, and ornamental Design for a Hygienic Soap Dish, of which the following is a specification, reference being had to the accompanying drawing, forming part thereof.

In the drawing

Fig. 1 is a top view of a hygienic soap dish, showing my new design;

Fig. 2 is a side view and

Fig. 3 is a sectional view thereof on line 3—3 of Fig. 1.

The outer surface of each of the shorter sides of the soap dish shown in the drawing is essentially plain.

I claim:

The ornamental design for a hygienic soap dish, substantially as shown and described.

BARNET D. KAPLAN.
